CIRCUIT CONTROLLING DEVICE

Minard A. Leavitt, Avon by the Sea, N. J., assignor to General Electric Company, a corporation of New York

Application December 3, 1942, Serial No. 467,746

4 Claims. (Cl. 200—87)

My invention relates to improvements in circuit controlling devices and more particularly to electromagnetically actuated circuit controlling devices and especially electroresponsive devices such as relays.

In some applications of circuit controlling devices, the relative severity of the duty demands ruggedness and simplicity of structure. Thus, for example, battery cutout relays used in connection with charging equipment must operate frequently. Moreover, their contact structure must not only be able to conduct relatively large currents but also to interrupt them. This frequency of operation and severe current duty affects most the contact structure, which is only too often the weakest point in the whole relay structure. Of course, the severity of the interrupting duty can be relieved by the addition of arc extinguishing devices. However, this adds complications besides increasing space requirements and cost, all of which it is desirable to avoid. Furthermore, in addition to relatively low initial cost, maintenance and repair call for simplicity and economy.

An object of my invention is to provide an improved circuit controlling device whose contact structure is capable of continuously carrying relatively large currents and yet has a relatively high interrupting capacity independently of arc extinguishing devices. Another object of my invention is to provide an improved electromagnetic circuit controlling device whose contact structure is simple and economical in first cost and easy to maintain and repair. A further object of my invention is to provide for an electromagnetically actuated circuit controlling device a simple and economical armature mounting which also functions as a movable circuit controlling member having a highly efficient and yet simple contact action.

In accordance with my invention, I provide for magnetically actuated circuit controlling devices an improved contact structure wherein the movable circuit controlling member is supported on an electric current conducting terminal-contact and bearing element in such a manner as to provide highly efficient current conduction. Also in accordance with my invention, I provide for magnetically actuated circuit controlling devices a simplified armature mounting which includes the above-mentioned contact structure to the movable circuit controlling member of which the armature is attached. Further in accordance with my invention, I provide for circuit controlling devices an improved armature and circuit

controlling member mounting which is simple in construction and easy to assemble and yet prohibits any false movements of the circuit controlling member and the armature attached thereto. These and other objects of my invention will appear in more detail hereinafter.

My invention will be better understood from the following description when considered in connection with the accompanying sheet of drawings, and its scope will be pointed out in the appended claims.

In the accompanying sheet of drawings, Fig. 1 is a side elevation of an electromagnetic circuit controlling device embodying my invention; Fig. 15 is a top plan view of the embodiment of my invention shown in Fig. 1; and Fig. 3 is an elevation in perspective of the embodiment of my invention shown in Fig. 1.

For the purpose of illustrating my invention, I 20 have shown a circuit controlling device of the electroresponsive type and more specifically a reverse current relay which is intended for use in direct current circuits. As shown, this relay comprises a magnetic structure in the form of 25 a U-shaped magnet 5 having two pole faces 6 and 7 and a cooperating armature 8. The magnet 5 is suitably secured to a base 9, preferably of insulating material for reasons hereinafter to appear.

30 In accordance with my invention, I provide means for mounting the armature 8 adjacent the pole faces 6 and 7 for movement relatively thereto in response to predetermined changes in the energization of the magnet 5 by energizing windings 10 and 11. As shown, this armature mounting means comprises a movable circuit controlling member 12 which, in the illustrated embodiment of my invention, is so superposed on the armature 8 that the longitudinal axes of the 35 member and the armature are substantially parallel with the member suitably attached to the armature on the side thereof opposite the poles 6 and 7. In other words, the member 12 is so superposed on the armature 8 that the current 40 conducting path of the member is substantially parallel to the flux path of the armature. As illustrated, the attaching means comprises screws 45 13 and lock washers 14 which serve rigidly to secure the member 12 to the armature 8.

50 For movably supporting the circuit controlling member 12 and the armature 8 attached thereto, I provide, in accordance with my invention, an electric current conducting terminal-contact and bearing element 15 which is positioned adjacent 55 one of the poles 7. For this purpose, it may be

suitably secured to the insulating base 9 through a conductively connected terminal post 16 provided with an insulating bushing 17. As illustrated, the terminal-contact and bearing element 15 is in the form of a bracket having a shelf portion or arm 18 on which one end of the circuit controlling member 12 rests. In order to prevent lateral movement of the armature 8, that is, transverse movement relatively to the poles of the magnet, the contact and bearing element 15 is provided with motion-limiting means such as an opening or through slot 19 into which the end of the armature adjacent the pole face 7 extends, as shown more clearly in Fig. 3. It will be observed that this slot 19 which extends clear through the vertical arm of the bearing element 15 also limits movement of the end of the armature 8 adjacent the pole face 7 away from this pole face. Also, the end of the electric current conducting member 12 which rests on the arm 18 is wide enough to bridge the slot 19.

In order to insure good conduction between the stationary contact element 15 and the movable circuit controlling member 12, the latter may be constructed with a beveled edge 20 so as to be in line contact with the contact element 15. For maintaining the knife edge contact between the circuit controlling member 12 and the element 15 at suitable pressure for the currents to be conducted, I provide means which is arranged to exert forces on the circuit controlling member tending to maintain one end thereof against the contact element 15 and to turn the circuit controlling member in one direction, clockwise as viewed in Figs. 1 and 2. As shown, this means is a biasing means in the form of a tension spring 21 connected between a post 22 on the base 9 and a post 23 rigidly positioned on the circuit controlling member 12. The angular position of the force exerted by the spring 21 is such that one component of the axial force of this spring tends to move the circuit controlling member 12 toward the base into high pressure contact with the contact element 15 and the other component of the axial force tends to turn the armature clockwise against a motion-limiting means, such as an adjustably positioned insulating back-stop 24. When the armature 8 is moved to the attracted position against the bias of spring 21, a contact 25 on the circuit controlling member 12 engages a stationary contact 26. It will be observed that in the attracted position the magnetic attraction between the armature and the pole faces 6 and 7 increases the contact pressure between the circuit controlling member 12 and its supporting contact element 15 and insures the necessary pressure between the contact elements 25 and 26.

For reverse current protection, the winding 10 may be assumed to be a current winding which has one terminal connected to a current conducting strap 27, which provides the mounting for the stationary contact 26 and the backstop 24. The other terminal 28 of the current winding 10 connects to a terminal post 29 mounted on the base 9. As shown, this post is also provided with an insulating bushing 30. The other energizing winding 11 is a potential energized winding, one terminal of which is connected to the conducting strap 27 and the other terminal to a terminal post 31 also mounted on the base 9.

Assuming now that the reverse current relay shown in the drawing is to be used in battery charging, then the terminal post 16 will be suit-

ably connected to the positive side of the battery, the terminal post 29 to the positive side of the generator, and the terminal post 31 to the negative side of both the battery and the generator, as indicated in Fig. 1. If the generator voltage is sufficient, the magnet 5 will be energized enough to attract the armature 8 and thereby close the contacts 25 and 26. This completes the circuit of the current coil 10 from the plus side of the battery as follows: the terminal post 16, the contact-terminal and bearing element 15, the circuit controlling member 12, the contacts 25 and 26, the conducting strap 27, the current winding 10, the lead 28, and the terminal post 29 to the positive side of the generator. If the generator voltage exceeds the battery voltage, the direction of the flow of current in the current winding 10 will be such that the magnetic effect of this winding will add to the magnetic effect of the potential winding 11 to maintain the armature 8 in the attracted position so that the generator can charge the battery. On the other hand, when the generator voltage is less than the battery voltage, the direction of the flow of current in the winding 10 will be such that the magnetic action of this winding is opposed to the magnetic action of the potential winding 11 thereby decreasing the holding effect of the magnet 5 on the armature 8, which will be actuated by the spring 21 to the position shown in the drawing to interrupt the battery charging circuit.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States is:

1. A circuit controlling device comprising a magnet having two pole faces, winding means for energizing said magnet, an armature, means maintaining said armature with its ends over said pole faces for angular movement relatively thereto comprising an electric current conducting member, said member and said armature being rigidly secured to each other with the conducting path of the member substantially parallel to the flux path of the armature and with the member on the side of the armature away from the pole faces, an electric current conducting terminal and bearing bracket positioned with one arm adjacent and substantially parallel to one of said pole faces, said arm being provided with a through slot for reception of one end of the armature to prevent lateral movement of said end and to limit movement of said end away from said one pole piece, and the end of said current conducting member adjacent said one pole piece being wider than said slot and positioned to bear on the side of said arm away from said one pole piece, a stationary contact positioned adjacent the other end of said pole faces and on the armature side of said current conducting member, and resilient means exerting a force on said current conducting member tending to maintain one end thereof on said bracket and the other end away from said stationary contact, and means for limiting the movement of said other end of the current conducting member away from said stationary contact.

2. A circuit controlling device comprising a magnet having two pole faces, winding means for

energizing said magnet, an armature, means maintaining said armature with its ends over said pole faces for angular movement relatively thereto comprising an electric current conducting member, said member and said armature being rigidly secured to each other with the conducting path of the member substantially parallel to the flux path of the armature and with the member on the side of the armature away from the pole faces, an electric current conducting terminal and bearing bracket positioned with one arm adjacent and substantially parallel to one of said pole faces, said arm being provided with a through slot for reception of one end of the armature to prevent lateral movement of said end and to limit movement of said end away from said one pole piece, and the end of said current conducting member adjacent said one pole piece being wider than said slot and positioned to bear on said arm and also having a beveled edge to engage said bracket in line contact, a stationary contact positioned adjacent the other of said pole faces and on the armature side of said current conducting member, resilient means exerting a force on said current conducting member tending to maintain said line contact and a force tending to move the current conducting member out of engagement with said stationary contact, and means for limiting the movement of said other end of the current conducting member away from said stationary contacts.

3. An electromagnet having an armature and an electric current conducting pivotal mounting for said armature comprising a conducting terminal and bearing element provided with an

- 10 opening for reception of one end of the armature to prevent lateral movement thereof, a conducting member rigidly secured to said armature lengthwise thereof and having one end positioned to bear on said element and also having a beveled edge to engage said element in line contact, a stationary contact positioned adjacent the other end of said conducting member for engagement thereby, and resilient means exerting a force on said current conducting member tending to maintain said line contact and a force tending to move the current conducting member out of engagement with said stationary contact.
- 15 4. An electromagnet having two spaced pole faces, an armature, and an electric current conducting pivotal mounting for said armature comprising a conducting terminal and bearing element mounted adjacent one of said pole faces and provided with an opening for reception of one end of the armature to prevent lateral movement thereof and also to limit movement of the end of the armature away from said one pole face, a conducting member rigidly secured to said armature lengthwise thereof and having one end positioned to bear on said element and also having a beveled edge to engage said element in line contact, a stationary contact positioned adjacent the other end of said conducting member for engagement thereby, and resilient means exerting a force on said current conducting member tending to maintain said line contact and a force tending to move the current conducting member out of engagement with said stationary contacts.
